(57) **CLAIM**

The ornamental design for a desk, as shown.

DESCRIPTION

FIG. 1 is a perspective view of a desk showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a first detail view thereof; and,

FIG. 9 is a second detail view thereof.

The broken lines are for environmental purposes only and form no part of the claimed design.
